PACKAGE AND METHOD OF MAKING SAME

Michael J. Milmoe, Glen Ellyn, Ill., assignor to
 F. B. Redington Co., Chicago, Ill., a corporation
 of Illinois

Application July 11, 1933, Serial No. 679,878

13 Claims. (CL 229—51)

The present invention has for an object, the making of a novel package which is impervious to moisture and which is provided with means for readily opening the same so that one can get at 5 the contents thereof.

Another object of this invention is to heat-seal the edges of the wrapper enveloping the articles, or articles in the package, and provide readily operable means associated with the package for 10 breaking the seal between adjacent layers of the wrapper.

Another object of this invention is to provide a very simple method for making a wrapper of the class described.

15 A still further object of this invention is to provide a double wrapper for an article or group of articles with means for readily opening both wrappers by a single movement of the opening means, the opening means being associated with 20 the package itself.

Another object of this invention is to provide means for opening a package which is sealed, at 25 one end only to permit access to the contents of the package so that portions of the contents may be removed without removing other portions thereof or destroying the wrapper about the portions which are not removed.

Other objects of this invention will appear hereinafter as the description thereof proceeds, the 30 novel features, arrangements, and combinations being clearly set forth in the appended claims:

In the drawing:

Fig. 1 is an isometric view showing the first step in the formation of a package;

35 Figs. 2 and 3 are similar views of subsequent steps in the formation of the package;

Figs. 4 and 5 are end elevations of the package in a further stage of formation;

40 Fig. 6 is an end view of the package with only the first wrapper in place and fully completed;

Fig. 7 is a side elevational view of the package shown in Fig. 6 with an additional wrapper about the same shown in cross-section; and

45 Fig. 8 is a perspective view of the package with parts thereof broken away for the sake of clearness.

The package constructed according to this invention comprises a group of articles wrapped in waxed paper and heat-sealed, and an additional 50 layer of foil about the first layer with means for opening the wrapper at one end of the package so as to make the contents thereof readily accessible. In Fig. 1 I have illustrated a sheet of waxed paper at 10 with a group of articles 11 which in the present instance are cylindrically shaped

pieces of candy of a rather well known type. Such candy must be protected from moisture in order to preserve the candy in the desired state. The formation of the package is illustrated rather schematically and particular apparatus for forming the package is not disclosed herein, but the essential steps will be described.

On the surface of the waxed sheet 10 upon which the candy 11 is placed, I lay a ribbon-like band 12 of fabric or any suitable means which will not 10 break under the required tension to open the package and preferably, although not necessarily, apply heat to cause the band to adhere to the surface of the sheet 10 at about the angle illustrated in Fig. 1 with respect to one edge of the wrapper. 15 I then take the end 13 of the wrapper and wrap this about the articles together with the band 12 by bringing the end 13 over the articles and then rolling the articles and sheet until the entire sheet is wrapped about the cylindrical surface presented by the group of articles 11 as is clearly illustrated in Fig. 2. This leaves cylindrical portions of the wrapper projecting beyond the ends of the groups of articles and I next proceed to fold these projecting cylindrical portions. Since the band 25 12 projects beyond one edge 14 of the sheet 10 when laid thereon, it is obvious that a portion of this band 15 will protrude beyond the cylindrical portion of the wrapper which projects beyond the end of the group of articles so that if the cylindrical portion is folded, over the end-most one of the articles to seal the package, the end 15 of the band will protrude therefrom making the same accessible to one desiring to open the package.

The next operation is to fold the cylindrical 35 portion inwardly against the end-most article adjacent that portion. This is done by successive steps. The first step is illustrated in Fig. 3 and comprises moving a portion 16 inwardly against the end-most article 17, the band 12 being carried 40 along therewith. The next step is to fold the portions 18 adjacent the portion 16 against the end of the article 17 as illustrated in Fig. 4. I next fold the portion 19 diametrically opposed to portion 16 over the end of the article and finally 45 fold the portions 20 intermediate the portions 19 and 18 against the article to completely fold the projecting portion of the wrapper against the end of the article 17 with the end 15 of the band extending in a position such as that illustrated in 50 Fig. 6.

As can be readily seen in Fig. 3, portions of the band 15 lie between adjacent layers of the waxed sheet 10 which extends beyond the group of articles and therefore when the successive folds 16, 55

18, 19, and 20 are made, the band 12 is so arranged that upon exerting a pull on the projecting end 15 thereof, the folds are caused to unfold. The folds are heat-sealed together either as they are formed or after all of the folds have been formed. The heating of the folds causes the wax of the paper to run together and hold the folds accordingly together when the heating means is removed and the wax has had a chance to solidify.

I next take the package illustrated in Fig. 6 and wrap the same in an additional layer of wrapping material such as tin foil in substantially the same manner with the result that projecting end 15 of the band in Fig. 6 which extends beyond the side of the package in that figure is moved inwardly due to the folding operation to such a position that it does not project beyond the sides of the article. This is accomplished by first moving the portion 21 of the foil wrapper 22 toward the protruding end 15 of the band and then against the end of the package, with the last or a subsequent fold 23 moved against the projecting end 15 of the band to cause the band to assume the shape illustrated clearly in Fig. 7 with a portion thereof still projecting in an accessible position outside of the package but not beyond the sides of the package as it does in Fig. 6.

The completed package is shown in Fig. 8 with the projecting end 15 of the band lying flatly against the end of the package but not beyond the sides of the package. This enables the package to be more readily handled and does not detract from the neat appearance thereof. Also in packages of this nature, it is common to apply a label preferably about the article and it is easier to do this if the projecting end 15 does not extend beyond the sides of the article but lies wholly within the outer circumference thereof.

Also it is apparent that those skilled in the art to which this invention pertains may make various changes in the particular construction and arrangement of parts without departing from the spirit of this invention, and therefore I do not wish to be limited except as hereinafter set forth in the appended claims.

In order to open the package, it is only necessary to grasp the end 15 of the band and exert a pull thereon. This causes the successive folds of foil to first open up and then subsequently the folds 16, 18, 19, and 20. Since the band is interposed between adjacent folds and winds in and out amongst the folds and adjacent layers of the waxed paper, it is obvious that the pull exerted on the band 12 will result in breaking the seal between adjacent folds and cause the opening of the end of the package after which the articles therein may be readily removed.

The advantage of using this arrangement is that the package may be quickly opened without one laboriously trying to separate the folds by prying underneath the folds with the finger nail or the like. Trying to open such a package by the use of a finger nail or similar instrument is not a very easy operation for the reason that the wax holds the folds quite close together and furthermore tends to run and conceal the edges of the folds. Also it is not always apparent just which is the last fold to be made and if one tries to pry open the first fold or any fold less than the last fold, it is more difficult to open the package.

Obviously if one wished to provide opening means at both ends instead of at one end of the package, this could be done without in any way changing the inventive concept, as it would

amount to a mere duplication, but it is usually only necessary to open one end of the package.

Having thus fully described my invention, what I claim as new and desire to obtain by Letters Patent is:

1. A package comprising an article, and a wrapper arranged thereabout having a series of pleated radially arranged folds and a band twining back and forth within said folds whereby when extension is exerted on said band, the folds 10 are caused to separate and become unfolded.

2. A package comprising a group of articles, a waxed wrapper arranged about said articles with portions thereof folded upon each other in radial arrangement with a continuous element arranged 15 within and amongst said folds in intimate contact therewith, the folds being heat-sealed together to provide a wrapper for said articles which is impervious to moisture.

3. A package comprising a group of articles arranged in end to end relation with a waxed wrapper arranged peripherally about the group of articles and sealed by folding portions of the wrapper in radially arranged folds against the end-most ones of the group of articles with a flexible open- 25 ing element arranged within and amongst the folds for breaking the seal between the folds when tension is exerted thereon.

4. The method of wrapping articles which comprises the steps of superimposing a flexible ele- 30 ment on a sheet of wrapping material adjacent one edge thereof at a slight inclination thereto with a portion of said flexible element extending beyond one edge of said wrapper, forming said wrapper into a tubular container about the con- 35 tents of said package with the edge of said wrap- per which lies adjacent said flexible element at one end of said tubular wrapper, folding the portions of said edge inwardly toward the contents of said package to form a plurality of overlapping folds, 40 and sealing said overlapping folds with a portion of the flexible element protruding from one of said folds in an accessible position.

5. A method of wrapping which comprises the steps of superimposing a flexible package opening 45 element on a sheet of wrapping material closely adjacent one edge thereof at a slight inclination thereto with a portion of said flexible element protruding beyond the said edge, shaping said wrap- per into a tubular container with the axis of said 50 tubular container substantially at right angles to said edge, whereby the protruding end of said flexible element extends beyond one end of said tubular container, and folding that end of said tubular container from which said end of said 55 flexible element extends to produce a series of overlapping folds with said flexible element ar- ranged amongst said folds, the said end projecting outside said container in an accessible position.

6. A method of wrapping which comprises the 60 steps of superimposing a flexible package open- ing element on a sheet of wrapping material closely adjacent one edge thereof at a slight incli- 65 nation thereto with a portion of said flexible element protruding beyond the said edge, shaping said wrapper into a tubular container with the axis of said tubular container substantially at right angles to said edge, whereby the protruding end of said flexible element extends beyond one end of said tubular container, folding 70 that end of said tubular container from which said end of said flexible element extends to produce a series of overlapping folds with said flex- 75 ible element arranged amongst said folds pro-

- jecting outside said container in an accessible position, and heat-sealing the folds together.
7. A method of wrapping which comprises the steps of superimposing a flexible package opening element on a sheet of wrapping material closely adjacent one edge thereof at a slight inclination thereto with a portion of said flexible element protruding beyond the said edge, affixing said flexible element to said wrapper against shifting movement with respect thereto, shaping said wrapper into a tubular container with the axis of said tubular container substantially at right angles to said edge, whereby the protruding end of said flexible element extends beyond one end of said tubular container, and folding that end of said tubular container from which said end of said flexible element extends to produce a series of overlapping folds with said flexible element arranged amongst said folds, the said end projecting outside said container in an accessible position.
8. The method of making a package as set forth in claim 5 which comprises the additional step of wrapping the package formed as in claim 5 with an additional sheet of wrapping material formed into a tubular container and sealed at its end by overlapping folds with a portion of said flexible element protruding from one of said folds.
9. A package comprising a wrapper arranged about an article and having a plurality of overlying folded portions, each folded portion consisting of a plurality of wrapper material layers, and an opening element arranged between the said wrapper layers with one part exposed whereby when tension is applied to the exposed part the folded portions of the wrapper are unfolded as units without the tearing of the wrapper material.

10. A package comprising a wrapper arranged about an article and having a plurality of radially arranged overlying folded portions, each folded portion consisting of a plurality of wrapper material layers, and an opening element arranged between the said wrapper layers with one part exposed. 5

11. The method of making a package which comprises arranging a wrapper peripherally about the body of an article with an end portion extending beyond the article body, arranging an opening element peripherally along the wrapper and diagonally to a side thereof adjacent said end portion, folding over the wrapper end against the article into a plurality of overlying folds, 15 arranging parts of said opening element among the folds, and exposing another part of said opening element on the outside of the wrapper.

12. The method of making a package which comprises arranging a sheet peripherally about 20 the body of an article with an end portion extending beyond the article body, arranging an opening element diagonally and peripherally along the sheet adjacent said end portion to form a tubular wrapper, folding over the wrapper end 25 against the article into a plurality of radially arranged overlying folds, arranging parts of said opening element among the folds, and exposing another part of said opening element on the outside of the wrapper. 30

13. A package comprising a wrapper wrapped about an article and having a plurality of folds, an element arranged within the package and entwined between a plurality of folds, said element having a part thereof extending outside of the 35 wrapper, whereby the folds may be released upon pulling the element.
